(57) **CLAIM**

I claim the ornamental design for a display board, as shown and described.

DESCRIPTION

FIG. 1 is a front perspective view of a first embodiment of a display board of the present invention.

FIG. 2 is a front view of the display board of FIG. 1.

FIG. 3 is a top view of the display board of FIG. 1.

FIG. 4 is a bottom view of the display board of FIG. 1.

FIG. 5 is a right-side view of the display board of FIG. 1.

FIG. 6 is an enlarged, right-side view of a lower end cap of the display board of FIG. 1.

FIG. 7 is a left-side view of the display board of FIG. 1.

FIG. 8 is a rear view of the display board of FIG. 1.

FIG. 9 is a front perspective view of a second embodiment of a display board of the present invention.

FIG. 10 is a front view of the display board of FIG. 9.

FIG. 11 is a top view of the display board of FIG. 9.

FIG. 12 is a bottom view of the display board of FIG. 9.

FIG. 13 is a right-side view of the display board of FIG. 9.

FIG. 14 is an enlarged, right-side view of a lower end cap of the display board of FIG. 9.

FIG. 15 is a left-side view of the display board of FIG. 9.

FIG. 16 is a rear view of the display board of FIG. 9.

FIG. 17 is a front perspective view of a third embodiment of a display board of the present invention.

FIG. 18 is a front view of the display board of FIG. 17.

FIG. 19 is a top view of the display board of FIG. 17.

FIG. 20 is a bottom view of the display board of FIG. 17.

FIG. 21 is a right-side view of the display board of FIG. 17.

FIG. 22 is an enlarged, right-side view of a lower end cap of the display board of FIG. 17.

FIG. 23 is a left-side view of the display board of FIG. 17.

FIG. 24 is a rear view of the display board of FIG. 17.

FIG. 25 is a front perspective view of a fourth embodiment of a display board of the present invention.

FIG. 26 is a front view of the display board of FIG. 25.

FIG. 27 is a top view of the display board of FIG. 25.

FIG. 28 is a bottom view of the display board of FIG. 25.

FIG. 29 is a right-side view of the display board of FIG. 25.

FIG. 30 is an enlarged, right-side view of a lower end cap of the display board of FIG. 25.

FIG. 31 is a left-side view of the display board of FIG. 25; and, FIG. 32 is a rear view of the display board of FIG. 25.

The portions of the display board shown in broken lines are for illustrative purposes only and form no part of the claimed design. The dot-dash-dot lines of the respective end caps of the display boards of FIGS. 1, 4-7, 9, 12-15, 17, 20-23, 25, and 28-31 define the boundary of the claimed design and form no part of the claimed design.

The stippling shown on the display board in FIGS. 17, 18, 25 and 26 represents a contrast of materials.
